US00D894729S

(12) **United States Design Patent** (10) Patent No.: **US D894,729 S**
(45) Date of Patent: ** Sep. 1, 2020

(54) **PACKAGE FOR TRANSPORT AND
HANDLING OF BIOLOGICAL MATERIALS**

(71) Applicant: **POLARITYTE, INC.**, Salt Lake City, UT (US)

(72) Inventors: **Denver Lough**, Salt Lake City, UT (US); **Edward Swanson**, Salt Lake City, UT (US)

(73) Assignee: **PolarityTE, Inc.**, Salt Lake City, UT (US)

(**) Term: **15 Years**

(21) Appl. No.: **35/001,535**

(22) Filed: **May 17, 2018**

(80) **Hague Agreement Data**

Int. Filing Date: **May 17, 2018**

Int. Reg. No.: **DM/103684**

Int. Reg. Date: **May 17, 2018**

Int. Reg. Pub. Date: **Nov. 23, 2018**

(57) **CLAIM**

The ornamental design for a package for transport and handling of biological materials, as shown and described.

DESCRIPTION

1. Package for transport and handling of biological materials
1.1 : Open front elevated perspective view of a package for transport and handling of biological materials;

1.2 : Perspective view of the package of Figure. 1.1;

1.3 : Front view of the package of Figure. 1.1;

1.4 : Left view of the package of Figure. 1.1;

1.5 : Right view of the package of Figure. 1.1;

1.6 : Back view of the package of Figure. 1.1;

1.7 : Bottom view of the package of Figure. 1.1; and

1.8 : Top view of the package of Figure. 1.1.

The broken lines, and lettering within the broken lines, form no part of the claimed design.

1 Claim, 8 Drawing Sheets
